[57] **CLAIM**

The ornamental design for a tire, as shown and described.

DESCRIPTION

FIG. 1 is a fragmentary developed plan view of a tire showing my new design;

FIG. 2 is an enlarged fragmentary plan drawing thereof; FIG. 3 is a reduced scale front elevational view thereof; (the same as rear elevational view thereof)

FIG. 4 is a left side elevational view thereof;

FIG. 5 is a right side elevational view thereof;

FIG. 6 is a top view thereof;

FIG. 7 is a bottom view thereof; and,

FIG. 8 is a perspective view thereof.

It is understood that the broken lines in the drawings show the fragmentary portions of the tire broken away for clarity of disclosure and form no part of the claimed design.
